UNITED STATES PATENT OFFICE.

PASQUALE PASCALE, OF NEW YORK, N. Y., ASSIGNOR TO DRI-STEAM VALVE CORPORATION, A CORPORATION OF DELAWARE.

STEAM VALVE.

Application filed November 12, 1925. Serial No. 68,717.

This invention relates to steam valves. It belongs to that class of valves described in my co-pending applications Numbers 545,638, filed March 22, 1922, and 751,796, 5 filed November 24, 1924.

These valves involve the principle of passing the steam into and through the valve to the point of use, through numerous attenuated openings or nozzles in the valve body, 10 which body is maintained practically at boiler temperature, so that the steam is divided into numerous jets, whereby its velocity is increased, and whereby the steam is "superheated" by the hot-metal contact, 15 and consequently dried or denuded of its moisture.

The valve about to be described is particularly adapted for use on a locomotive, but its use is not so limited.

20 The tendency in building present day locomotives is to limit their height and incidentally limit the height of the steam dome, and the steam space within the boiler, and such limitation has confined the height of 25 the locomotive to such an extent that difficulties are being encountered in order to insure the proper life and measurements of the superheating equipment, and this is because an excessive amount of water is drawn 30 over through the throttle into the superheater. By reason of the evaporation of this moisture, an entrained water scale is formed 35 on the superheating surface, due mainly to deposits of sulphate of lime and magnesia, the result being to decrease the efficiency of the superheater and to increase its cost of maintenance.

The objects of the invention are manifold. One object of the invention is to so construct 40 the valve that it may occupy small space, and the same space usually occupied by the ordinary throttle valve, and is adapted for installation in the same manner without alteration of the usual control of the valve.

45 Another object of the invention is to so construct the valve that it will deliver steam in a dry state into the superheater, regardless of the percentage of moisture at the inlet of the valve, and return the small amount 50 of condensation incident to its use, to the boiler. A further object is to provide a valve an incident of which is, that superheated steam is delivered to the engine cylinder with constancy in temperature, or at

least with infinitesimal loss or reduction in 55 temperature.

An incident of the construction of the present valve, is increase in boiler efficiency, in that boiler capacity is increased without increasing the boiler size. Boiler efficiency 60 means fuel economy, since fuel consumption is lessened by the increased boiler efficiency for a given evaporation, and the fact that with the valve about to be described, the water consumption is lessened by reason of 65 the direct return of the separated water into the boiler, there necessarily results water economy. Furthermore, the superheater efficiency is increased by reason of the delivery to it of dry steam, and its life is 70 greatly prolonged.

In the drawings illustrating the invention, Figure 1 is a top plan view of the valve, partly in horizontal section.

Figure 2 is a central section, the valve 75 being closed.

Figure 3 is a cross section taken on the line A—B, of Figure 2.

Figure 4 is a side elevation.

Figure 5 is a broken elevation of the valve 80 body showing the ports therein.

Figure 6 is a broken sectional view showing a modified form of segmental blades or vanes which constitute a turbine or cage through which the steam enters the ports 85 in the valve body, the valve being partly open.

Figure 7 is a plan view of a portion of one 90 of the plates constituting a part of the cage, of the form shown in Figure 6.

Figure 8 is a detail section taken through two of said plates, say on plate C—D of Figure 7.

Referring to the drawings, the numeral 1 designates the valve body formed with an 95 inverted dome-shaped portion 2, and continuous wall 3, which wall is provided at intervals with ports 4. Body 1 is flanged as indicated at 5, and bolts 6 secure it to corresponding flanges 7 of the outlet pipe 8. 100 The body is further formed with an annular enlargement 9, formed with a continuous valve seat 10, adapted for a close fit with the lower bevelled end 11, of the valve 12.

Adjacent the valve seat there is formed in the valve body an annular sump 13, intersected by a suitable number of drain-holes 14, so that the moisture of which the steam

is denuded, or the water of condensation, is directly returned to the boiler.

Within the valve body is a cylinder 15 formed with a lateral extending flange 16 at its lower end adapted to fit in an annular recess 17 in the valve body, to which body the cylinder may be secured by screws 18. In order to make a tight fit between the valve body and the outlet pipe 8, I preferably recess the flanged portion 7 for the reception of the flange 17 so that said flange and the portion of the valve body immediately adjacent, serves as a gasket. The upper portion of the cylinder 15 is provided with many attenuated openings or nozzles 19, arranged in circumferential rows, the openings flaring slightly from the inner periphery of the cylinder.

The valve body is provided at proper intervals with apertured lugs 20, to which are secured by bolts 21 a corresponding number of ears, 22, integral with a flat ring 23, which rests upon the ledge 24 of the enlargement 9 of the valve body. The numeral 25 designates an upper ring provided at intervals with apertured studs 26, for the passage of short bolts 27, by which sections of the ring may be secured together. Interposed between these rings 23 and 25 are a series of vanes 28, slightly curved, as best shown in Figure 1, constituting what may be termed a "turbine" or cage. These vanes are arranged tangential to the valve body and the different series of vanes are in quadrant arrangement with their openings so disposed that steam entering between them will be deflected in opposite directions for each lateral half of the valve body, so that the steam will come into the valve body with a whirling motion and be directed similarly through the ports in the valve body and through the nozzles or attenuated perforations in the cylinder 15, with a velocity greater than the velocity of the steam in the space surrounding the valve.

The valve 12 is provided with a central enlargement 29 having therein a recess 30. Let into the enlargement 29, is a sleeve or bushing 31, which is held therein by threads 32. This sleeve is held in proper position by a set screw 33. Slidably in this sleeve is the pilot valve 34, provided at its lower end with a head 35. The upper part of the sleeve is bevelled as indicated at 36, and serves as a seat for the correspondingly bevelled portion of the pilot valve. The lower part of the pilot valve stem is provided at intervals with splines 37, by which the stem is spaced properly from the inner periphery of the sleeve, so as to permit steam, when the valve stem is lifted, to flow into the space between the valve body and the valve to balance the valve. As shown in the detail Figure 6, the upper portion of the pilot valve is recessed 60 and threaded internally as indicated at 38,

and the head 35 is provided with a shank that extends through the valve stem and is threaded into said threaded opening.

The numeral 39 designates the control levers. These extend vertically of the valve 70 as a whole, and their upper ends are connected by a cross bar 40, held between the arms of a yoke 41, by a pin 42.

These levers 39 are pivotally connected at their lower ends to two bell crank levers 44, 75 which levers are fixed to a transverse pin 45, rockably supported in two properly spaced lugs 46, cast with the steam pipe connected with the valve body. A bell crank lever 47 is provided, to whose upper end is pivoted 80 at 48, the valve operating rod 49. It is through this operating rod, and connected parts, that the valve 12 is slidably operated upon the valve body to open the ports more or less as the exigencies of the case may require, to permit more or less steam to be admitted to and through the nozzles 18.

In operation, steam surrounding the valve in the steam dome or steam space in which it may be located, will upon raising the pilot 90 valve through the instrumentality of the control levers, lift said pilot valve from its seat sufficiently to permit steam to flow into the recess 30, round the stem of the pilot valve, and into the space between the valve 95 body and the valve. This immediately establishes a balance between these two parts. On further movement of the operating lever, say for instance to open the valve to admit steam to its work, the head 35 will engage 100 the lower part of the central enlargement of the valve, and carry the valve upward, opening the ports more or less as has been just stated.

The steam passing through the blades of 105 the turbine is directed generally in the directions indicated by the arrows, only a few of which are shown, and delivered to the space between the cylinder 15 and the wall of the valve body, and thence through the 110 nozzles into the cylinder and into the outlet pipe. It will be apparent from Figure 1 that the wall of the cylinder 15 is spaced considerably from the wall of the valve body, and that the ports are so arranged 115 that they are larger than the portions of the wall of the valve body that is between them.

With the exception of the formation of the cage or turbine the construction shown in Figures 6, 7, and 8 are identical with that 120 already described. In this embodiment the turbine is constituted by a series of concavo-convex rings or plates 49, provided at intervals with lugs 50, the lugs being provided with apertures 51 for the passage of 125 bolts 52, the lugs being adapted to rest one upon the other to hold the rings properly spaced apart, to form steam openings 53, the openings being so shaped that the steam will pass between them in entering in an 130

upwardly oblique direction, and then in a downward oblique direction, to be again deflected and distributed with a whirling motion in the space between the valve body and 5 the valve, and from thence through the nozzles.

Claims—

1. In a steam valve, a hollow body having steam ports therein, a cylinder in said body 10 provided with numerous small holes therein constituting nozzles, a valve seat on said body outside the nozzles, means surrounding the body outside thereof, and outside the nozzles for breaking up the steam into attenuated streams, and directing the resulting currents through the ports and toward all 15 of the nozzles, a stop valve enveloping a part of the body and slidable over said ports, between said means and nozzles, and adapted 20 to seat upon the seat on the body.

2. In a steam valve, in combination, a hollow body having steam ports therein, a cylinder in said body provided with numerous holes therein, arranged circumferentially 25 in said cylinder and constituting nozzles, and an annular valve seat on said body outside the nozzles, a cage surrounding the valve body and formed of a series of vanes through which the steam passes and is divided into attenuated streams in entering 30 the valve, the vanes being so positioned as to direct the resultant currents toward all of the nozzles, a stop valve enveloping the body and slidable over the ports, in said body, and between the vanes and nozzles, and adapted to seat upon the annular valve seat.

3. In a steam valve, in combination, a hollow body having steam ports therein, a cylinder in said body and provided with numerous holes therein constituting nozzles, an annular seat surrounding said body and located below the ports, a cage including a plurality of vanes between which the steam passes to the ports in said body and is divided into attenuated streams in entering the valve, and directed toward all of the nozzles, a stop valve enveloping the upper part of the body and slidable over the 45 ports therein and between the vanes and nozzles, said stop valve being adapted to seat upon the annular seat on the body.

4. In a steam valve in combination, a hollow body having steam ports arranged 55 therein, an annular valve seat on said body below the ports, a cylinder within the body and provided with numerous holes constituting nozzles, a cage surrounding said body outside the nozzles, said cage including numerous vertically arranged vanes on axes 60 different from the axis of the cylinder and adapted to project the steam obliquely

against said nozzles, for the purpose set forth, and a stop valve enveloping the upper part of said body and slidable between the 65 vanes and the nozzles and adapted to seat upon the seat and to be operated to open the ports more or less, as may be required.

5. In a steam valve, in combination, a hollow body having steam ports arranged 70 therein, an annular valve seat below said ports, a cage surrounding said ports and outside thereof, said cage comprising upper and lower rings connected by numerous vertically arranged vanes which provide spaces 75 for the admission of steam, said vanes being so arranged as to direct the steam in attenuated currents toward the ports, a cylinder in the body and provided with numerous holes arranged circumferentially therein and 80 in rows, said nozzles flaring toward the ports, a stop valve enveloping the upper part of the body and slidable between the ports and cage and adapted to seat upon the annular seat upon the valve body. 85

6. In a steam valve in combination, a hollow body having steam ports therein, a valve seat on said body and an annular seat on said body and an annular sump adjacent said seat, there being communicating with 90 said sump a series of drain holes whereby water of condensation will be returned to the boiler, a cage surrounding the body and including numerous vanes in quadrant series, the vanes of one quadrant on the lateral 95 side of the valve being curved in one direction and those in the adjoining quadrant curved in the opposite direction, the spaces between the vanes forming attenuated openings through which steam is projected in an 100 oblique direction, a cylinder in the valve body provided with numerous holes arranged in rows circumferentially of the body and constituting nozzles for the passage of steam into said body, and a stop valve enveloping the upper part of the body and 105 slidable between the cage and the nozzles.

7. In a steam valve, in combination, a hollow body having steam ports therein, a cylinder in said body provided with numerous holes constituting nozzles, a valve seat on said body and outside of the nozzles, means surrounding the body also outside the nozzles for breaking up the steam into attenuated streams and directing the resultant 110 currents obliquely toward the ports in the hollow body and toward all of said nozzles, a stop valve enveloping the upper part of the body and slidable over said ports, and between said means and nozzles and adapted 115 to seat upon the valve seat.

In testimony whereof he affixes his signature.

PASQUALE PASCALE.
